UNITED STATES PATENT OFFICE

JOHN M. CLARK, OF DETROIT, MICHIGAN, ASSIGNOR TO UNIVERSAL BUTTON FASTENING & BUTTON CO., OF DETROIT, MICHIGAN, A CORPORATION OF MICHIGAN

BUTTON

Application filed July 23, 1929. Serial No. 380,290.

This invention relates to so-called flexible buttons and among other objects, aims to provide an improved and inexpensive button of this character in which security of fastening is not sacrificed to obtain flexibility.

The invention may be readily understood by reference to one illustrative button embodying the invention and illustrated in the accompanying drawings.

10 In said drawings:

Fig. 1 is a sectional elevation of the button fastened to fabric or the like.

Fig. 2 is a bottom plan view of the button, the attaching fastener prongs being shown 15 in section.

Fig. 3 is a sectional elevation, partly in section, showing the so-called flexible characteristic of the button, namely, its ability to tilt.

The illustrative button comprises the button body, a flexibly connected fastener engaging element constituting also the button base, and a protective or decorative surfacing for the button head.

The button body 10 is advantageously 25 made of steel or other metal in the form of a rod or similar stock (which is quite inexpensive compared with sheet metal stock) and is brought into the illustrated shape by one or more die pressing operations upon a blank or 30 slug cut from the rod stock. The button head may advantageously be improved in appearance as well as protected by being provided with a superficial coating such as protective and decorative enamel or metal plating.

35 Such surfacing is illustrated herein in the form of a separate shell 11 of relatively thin metal which is either itself rustproof or treated superficially to render it rustproof. Such decoration may include any desired embossing or trade-mark on the top of the button head, depending upon the desires of the purchaser.

The shell 11 is secured to the button head by crimping its marginal flange 12 underneath the button head which in 40 this case is offset or rabbeted so that the outer surface of the crimped flange 12 lies flush with the under surface of the head.

The shank 13 of the button being in this case an integral part of the button body and, 45 therefore, of solid metal, is made in a much

smaller diameter or thickness and with greater strength than a hollow shank button made of more expensive sheet metal. Its smaller diameter permits it to be buttoned through button holes without buckling the 55 cloth as frequently happens with buttons whose necks or collets are larger than the space in the button hole provided for their reception.

Flexibly connected to the end of the shank 60 is a button base member in the form of a fastener receiving element 14 provided with fastener engaging means. The loose connection between the fastener receiving element 14 and the button gives the button the desired 65 flexibility, namely, the capacity to tilt, and in this case to rotate, relative to the point of attachment of the button. Such loose connection is effected in the present instance by giving the element 14 a cup shape which enables it to embrace the enlarged extremity 15 of the button shank. The flange 16 of the element 14 is crimped or turned in sufficiently 70 to prevent the extremity 15 from being withdrawn but does not embrace the latter so 75 tightly as to destroy the aforesaid flexible connection.

As shown, the button is attached by a pronged fastener upset within the button base 14 which draws the base tightly against 80 the intervening cloth. If a double pronged fastener 19, such as that here shown, is employed, the button base is provided with a pair of openings and an intervening transverse bar 17 (which in the present case is advantageously formed integral with the base by punching a pair of openings in the base, see Fig 2); and the prongs 18 of the fastener are bent around the bar from opposite 85 sides. If a single prong fastener be employed the button base is preferably formed with a single opening only slightly if at all, larger in size and shape than the fastener prong. By either means of attachment the cloth 21 is firmly gripped between the head 90 of the fastener and the button base, both of which are adequate in size to grip a substantial area of cloth and avoid concentration of strain on the portion 22 of the cloth which is immediately adjacent the attaching prong. 95

For the purpose of readily upsetting the fastener inside the button base, the button shank 13 is advantageously provided with a concave surface or die cup 20 which serves to upset the fastener tightly against the button base. The operation of forming the die cup may be advantageously used to form the enlarged extremity 15 of the button shank, i. e., some of the metal displaced to 10 form the die cup, is utilized to create the enlargement 15.

The button base 14 being of substantially larger diameter than that of the shank 13 prevents a suspender loop or other element 15 engaging the button from wedging between the button base and the fabric to which the button is attached, with the possibility of loosening the button and tearing the cloth. That is, the part engaging the button is held 20 away from the base of the button by the element 14 and located in the seat on the button shank of much smaller diameter (provided between the button base and the button head).

The illustrative button is not only an inexpensive button since it is made of but two 25 relatively inexpensive elements (not including the optional decorative or protective finish for the button head) but its construction is such as to lend itself well to economic manufacture, requiring little or no handling. For example, the button body 10 may be formed in a series of operations which involve no manual handling, and, without intervening manual handling; then the base member 14 (formed by a simple punching and pressing operation) may be easily attached. While the button is advantageously adapted to be formed economically in the 40 aforesaid or a similar manner, its manufacture is obviously not limited to full automatic manufacture or to manufacture according to any definite sequence of operation.

The button is further constructed and arranged for use with button attaching machines now on the market which, if the button be designed for attachment by a double pronged fastener, orient the button attaching bar, that is, the bar 17 in this case, relative to the attaching fastener prongs—so that when the attaching dies are brought together the fastener prongs will pass on opposite sides of the bar 17. Such orienting operation is effected by the rotation of the 55 button bar until it arrives at a predetermined position relative to the fastener prongs. During such orienting operation the extremity of the button shank lies flat against the bottom of the button base (the button being fed head up) so that it may be oriented and attached like an ordinary non-flexible button.

The illustrative button, therefore, combines flexibility with the security and efficiency of attachment afforded by the double

pronged fastener, without requiring the use of a special attaching machine.

Obviously the invention is not limited to the details of the illustrative button since these may be variously modified.

Having described one embodiment of my invention, I claim:

1. A flexible button comprising in combination a button head, a solid button shank integral with said head, and a cup shaped fastener receiving member loosely embracing the lower end of said shank to provide a flexible connection for said button head, said fastener receiving member being provided with means for receiving a button fastener. 75

2. A flexible button comprising in combination a button head, a button shank, and a fastener receiving member flexibly secured to said shank, said fastener receiving means being constructed and arranged to receive 85 a two pronged fastener and having a bar around which the prongs of the fastener may pass, the end of said shank being provided with an integral die having a concave surface for bending the fastener prongs about said bar. 90

3. A flexible button comprising in combination a button head, a solid button shank, and a fastener receiving member flexibly secured to said shank and having means for receiving a pronged fastener, the end of said shank being recessed to provide a curved die surface to upset the fastener after it has entered the fastener receiving member. 95

4. A flexible button comprising in combination a button head, a button shank, and a cup shaped fastener receiving member loosely surrounding and embracing the lower end of said shank to provide a flexible connection for said button head, the end of said shank being recessed to provide means for upsetting the fastener inside said receiving member. 100

5. A flexible button comprising in combination a button head, a shank therefor having its lower end enlarged, and a cup shaped fastener receiving member loosely surrounding and embracing said enlarged end to provide a flexible connection for said button, said fastener receiving member having a bar about which the prongs of a double pronged fastener may be secured. 110

6. A flexible button comprising in combination a button head, a shank therefor having its lower end enlarged, and a cup shaped fastener receiving member loosely embracing said enlarged end to provide a flexible connection for said button, and being constructed and arranged to be engaged by a pronged fastener, the end of said shank being recessed to provide a die for upsetting the pronged fastener inside said receiving member. 120

7. A flexible button comprising in combination a button head, a shank therefor having its lower end enlarged, and a cup shaped 130

fastener receiving member loosely embracing
said enlarged end to provide a flexible con-
nection for said button and provided with a
bar for engaging a double pronged fastener,
5 the end of said shank being provided with a
concave surface to serve as a die to curl the
prongs of the fastener over said bar.

In testimony whereof, I have signed my
name to this specification.
